(57) **CLAIM**

The ornamental design for razor packaging, as shown and described.

DESCRIPTION

FIG. 1 is a perspective view of a showing my new design for razor packaging in which in which an array of razor packing colors is shown (e.g. green, purple and pink) and the product button is the same color as the packaging label;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dashed broken lines are directed to the environment and are for illustrative purposes only and form no part of the claimed design. The hatching indicates the green, purple or pink color of the product label and button.
